POULTRY FEED CHAIN LOADER

Gerald L. Kitson, 9709 Belding Road,
Rockford, Mich. 49341

Original design application June 26, 1972, Ser. No.
266,488, now Patent No. 231,370. Divided and this
application Apr. 16, 1974, Ser. No. 461,382

Term of patent 14 years

Int. Cl. D12—05

U.S. Cl. D55—1 C

FIG. 1

FIG. 5

FIG. 2

FIG. 3

FIG. 4

FIG. 1 is a perspective view of a poultry feed chain loader embodying my new design.

FIG. 2 is a top view of the poultry feed chain loader shown in FIG. 1.

FIG. 3 is an elevation of the poultry feed chain loader of FIG. 1 and FIG. 2, showing the side thereof not visible in FIG. 1.

FIG. 4 is an end elevation of the poultry feed chain loader of FIGS. 1, 2, and 3 showing the end thereof not visible in FIG. 1.

FIG. 5 is a sectional elevation of the poultry feed chain loader viewed at 5—5 in FIG. 2.

This application is a divisional of my copending application Ser. No. 266,488, filed June 26, 1972, now Pat. No. D. 231,370, entitled Reversing Poultry Feed Hopper.

I claim:

The ornamental design for a poultry feed chain loader, as shown and described.
